VAPOR ELECTRIC LAMP INSTALLATION

Adolph Warsher, Maywood, N. J., assignor to Duro
Test Corporation, North Bergen, N. J., a cor-
poration of Delaware

Application February 20, 1941, Serial No. 379,760

4 Claims. (Cl. 173—328)

Among the objects of the present invention are to provide equipment of reduced cost but of greatly improved and finished appearance by which the installation of vapor electric lamps is facilitated, with complete security thereof electrically and mechanically.

Another object is to provide a simple and inexpensive lamp socket unit, for the above purpose, that may be applied instantly to a lamp carrying fixture and that accommodates the end prongs of a vapor electric lamp installed therein, all with the attainment of the facility and security above set forth.

In the accompanying drawing in which are shown one or more of various possible embodiments of the several features of the invention,

Fig. 1 is a plan view of the spring socket unit,

Fig. 2 is a transverse sectional view taken on the line 2—2 of Fig. 1.

Fig. 3 is a transverse sectional view taken on line 3—3 of Fig. 1,

Fig. 4 is a rear plan view of the device,

Fig. 5 is a view in longitudinal cross-section with parts broken away showing one embodiment of the complete installation,

Fig. 6 is a perspective view of a modified form of socket block, and

Fig. 7 is a fragmentary transverse section through Fig. 6.

Referring now to the drawing, the invention involves the use of a spring urged socket for one or both terminal ends of the lamp. The socket unit in one embodiment involves a socket block 10 carrying the contact springs 11 for the prongs or other terminal elements 12 at one end of the lamp.

The block 10 is assembled to a face plate 13 through a central aperture 14 in which it is disposed. The block is slidably mounted in the face plate and spring urged outwardly to a limiting position determined by projections, desirably diametrically opposite lugs 15 and 16 on the socket block which engage the inner side of the face plate 13.

In the embodiment of the construction specifically shown in Figs. 1 to 4, the socket block is of molded material with passages 9 therethrough enlarged at their outer ends as shown for accommodating the contact springs 11. Stems 8 of contact springs 11 extend through the block and are twisted at their protruding ends 11' serving for anchoring the contacts in place and for attachment thereto of terminals or wire leads (not shown). The lugs 15 and 16 are unitary with a sheet metal ring 17 molded into the block and

concentric therewith. Rods 18 and 18 headed at their forward ends 20 extend through the face plate and also through the apertures 21 in the lugs 15 and 16 and are encircled by coil springs 22 which react against a stop, desirably in the form of a cross strap 23 connecting the inner ends of the rods, which are headed thereover at 24. While the face plate may be of any of numerous possible constructions, a conventional outlet box plug button with peripheral spring fingers 25 is desirably employed.

The unit described lends itself readily for application to more or less conventional fixtures for vapor electric lamps, more especially those commonly used for fluorescent lamps. Such fixtures include ordinarily a base 26 which may house the starting appliance diagrammatically indicated at 27 and end walls or brackets 28 and 29 that mount the lamp socket units. The end brackets have circular holes *h* of size to accommodate the face plate of the spring socket. It will be understood that the electric wires will be connected to the terminal lugs 11' on the inner ends of contact sleeves, whereupon the spring socket unit would be simply snapped into the hole *h* by the spring fingers 25 on its face plate 13 as shown in Fig. 5, which completes the fixture assembly. The lamp is readily installed in the fixture by inserting the prongs into the contact sleeves 11 of one socket block (illustratively the right one in Fig. 5), pressing the latter inward to bring the opposite prongs into alignment with the contact sleeves at the opposite end as shown in Fig. 5, whereupon the expansion of the compressed springs 22 will urge the socket block outwardly, securely to retain the lamp in position with its prongs in the respective contact sleeves at the opposite ends of the fixture.

As a matter of uniformity and convenience, the spring socket unit shown is preferably used at both brackets of the fixture, so that the lamp can be inserted by introducing either end first. It will be understood, however, that the structure would be operative if one of the sockets only were of the spring type and the other were of rigid type.

In Figs. 6 and 7 is shown an additional embodiment in which the socket block comprises a sheet metal cup 30 with outstanding lugs 31 having a pair of insulating plates or disks 32 and 32' desirably of laminated plastic peripherally clamped against the inturned rim 33 by tangs 34 struck out from the side wall thereof. The contact sleeves 35 protrude beyond the cup 30 to terminal lugs 35'. They are mounted in corre-

sponding apertures through insulating plate 32' and their root ends are outturned at 36 to form flanges clamped between the two plates 32 and 32'. The outer disk 32 has apertures 37 smaller than those accommodating sleeves 35 through which the prongs 12 are introduced. The socket block of Figs. 6 and 7 is simply an alternative for that of Figs. 2 and 3 for which it may be substituted in a spring socket unit otherwise identical with that of Figs. 1 to 4.

As many changes could be made in the above construction and many apparently widely different embodiments of this invention could be made without departing from the scope of the claims, it is intended that all matter contained in the above description or shown in the accompanying drawing shall be interpreted as illustrative and not in a limiting sense.

Having thus described my invention, what I claim as new and desire to secure by Letters Patent is:

1. A spring socket unit for a vapor electric lamp comprising a face plate, a socket block extending through a corresponding aperture in said plate and having contacts therein, lugs unitary with said block and radiating therefrom along the underside of said face plate, rods through said face plate and said lugs, coil springs about said rods and means sustaining said coil springs to press against said lugs.

2. A spring socket unit for a vapor electric lamp comprising a face plate, a socket block ex-

tending through an aperture therein, contact sleeves through said block for terminal prongs of a lamp, a stop plate rigid with said block and extending along the rear of said face plate, rods 5 through said face plate and said stop plate, coil springs encircling said rods and a backing plate connecting the free ends of said rods and supporting said coil springs.

3. A spring socket unit for a vapor electric lamp comprising a metal face plate, an insulating molded socket block having a pair of contact sleeves therein for accommodating the prongs of a lamp and having lateral diametrically opposite stop lugs molded therein, a pair of parallel rods extending through said face plate and said stop lugs, coil springs thereabout and a connecting plate between the free ends of said rods, sustaining the corresponding ends of the coil springs.

4. A spring socket unit for a vapor electric lamp, comprising a circular face plate having peripheral spring tongues adapted to be snapped into a corresponding opening of a support fixture, a pair of parallel rods carried by said plate, coil springs thereabout, means sustaining the ends of said springs and a socket block protruding through a central aperture in said face plate and equipped with contact sleeves, said block having lugs rigid therewith traversed by the respective rods and against which the ends of the coil springs react.

ADOLPH WARSHER.
